UNITED STATES PATENT OFFICE.

CHARLES J. SIBBALD, OF TROY, NEW YORK, ASSIGNOR, BY MESNE ASSIGNMENTS, TO
FREDERICK OSANT COMPANY, OF NEW YORK, N. Y., A CORPORATION OF NEW YORK

SEWING-MACHINE.

1,242,875.

Specification of Letters Patent.

Patented Oct. 9, 1917.

Application filed January 2, 1912, Serial No. 669,049. Renewed September 25, 1916. Serial No. 122,023.

To all whom it may concern:

Be it known that I, CHARLES J. SIBBALD, of Troy, in the county of Rensselaer and State of New York, have invented certain new and useful Improvements in Sewing-Machines, of which the following is a specification, reference being had to the accompanying drawings, forming part thereof.

This invention has reference to improvements in sewing machines and relates particularly to mechanism whereby the feeding movement of the thread may be so restrained by auxiliary restraining means, that said thread may be broken.

One object of the invention is to so construct a sewing machine that at the completion of a sewing operation a supply of thread may be pulled through the tension, said supply of thread being preferably sufficient to start a new sewing operation, and that, as a result of the pulling out of said thread, the movement of the thread toward the work is so restrained that the thread may be broken by exerting a strain thereon.

Other objects of the invention will appear from the following description.

The invention consists in the sewing machine having the thread tension, the auxiliary thread restrainer and means for exerting a strain on the thread.

The invention also consists in such other novel features of construction and combination of parts as shall hereinafter be more fully described and pointed out in the claims.

Figure 1, represents a side elevation of portions of a sewing machine illustrating this invention.

Fig. 2, represents a cross sectional view of portions of the same as taken on line 2—2 Fig. 1, the work carrier or button clamp being omitted.

Fig. 3, represents a side elevation of portions of the machine showing a modified form of the thread puller and strainer actuating mechanism.

Similar numerals of reference designate corresponding parts in all figures.

As shown in the drawings the improvement is disclosed as applied to a button sewing machine of well known construction having the bed plate 5 furnished with the head

6 and supplied with the usual stitch forming devices comprising the needle bar 7 slidably mounted in the head 6 and provided with the needle 8; and the looper 9 mounted on the shaft 10 located beneath the bed plate 5. Below the bed plate 5 is located the worm shaft 11 which drives the pinion 12 of the cam 13 journaled on the stud 14 which depends from the bed plate 5. The usual base 15 of the button clamp having the pivoted work holder mechanism 16 is moyably mounted on the bed plate 5 and is actuated in the usual manner to effect the vibration of the button and fabric to which the button is to be sewn with respect to the path of the needle.

The head 6 is furnished with the thread tension 17 and with the thread guides 18, 18 and 19 through which the thread *a—a* is guided in its movement from the tension 17 to the needle 8. From the side of the head 6 extend the ears 20, 20 and 21, 21. In the ears 20, 20 is mounted the shaft 22 on which is, preferably, rotatable the sleeve 23 having the lever 24 and the arm 25 furnished with the thread puller wire 26. Retractive rotation of the sleeve 23 is effected by means of the coil spring 27 embracing the shaft 22 and having its ends engaged respectively with said sleeve 23 and with one of the ears 20. Said lever 24 is operated to swing the arm 25 in a path transverse to the direction of the thread *a—a* by means of the rod 28 pivotally engaged with the lever 23 and slideable through a comparatively large perforation in the bed plate 5, the lower bent end 29 of said rod 28 being engaged with and actuated by the cam throw 30 of the cam 13 which cam 30 is preferably so located on the periphery of said cam 13 that at the completion of a group of stitches said cam 30 has acted on the end 29 of rod 28 to move downward the lever 24 and swing the arm 25 and the thread puller 26 to the positions shown in dotted lines in Fig. 2 and to thereby pull the thread *a—a* transversely from its normal path at a point between the thread guides 18, 18.

In the ears 21, 21 is journaled the shaft 31 having the lever arms 32 and 33 of which the former is connected with the rod 34, usually operated by some well known

pedal mechanism, while the latter arm 33 is connected by the chain 35 with the forward or free end of the button clamp or work holder 16 whereby after the completion of a sewing operation the free end of said button clamp or work holder 16 may be moved upward, that is, away from the looper 9.

In Fig. 3 of the drawings is shown a modification of the device in which shaft 31 is extended in length to form the support for the sleeve 23 of arm 25 and said sleeve 23 is pinned to said shaft 31 so that said arm 25 is swung outward by the partial rotation of shaft 31 and is retracted by the spring 27 acting against said arm 25 and against a fixed part of the machine.

The cam path or groove of cam 13 in which the follower 15' of the work holder 20 vibrating mechanism is engaged is shaped in the usual manner to effect, through said usual vibrating mechanism, a series of vibrations of the work holder relative to the path of the needle and finally to hold said 25 work holder at rest while two or more downward movements of the needle are made to form chain stitches which become, so called, knots when drawn tight. Approximately as such chain stitches are completed cam member 30 of cam 13 acts on the end 29 of rod 28 to effect the swinging of lever arms 24 and 25 and the thread puller 26 whereby the thread *a—a* is drawn laterally from between the guides 18, 18 as 30 indicated in Fig. 2 and thus resistance, additional to that of the usual tension 17, is offered to the movement of the thread *a—a* by the guides 18, 18 and the thread puller 26 so that when a suitable strain is exerted 35 on said thread, as by the lifting of the work holder 16 carrying with it the group of stitches last formed, the thread breaks usually at the point of juncture with the last 40 stitch.

When the machine is started to sew the next group of stitches the shape of cam member 30 permits the upward movement of rod 28 and the retractive movement of arm 25 and its thread puller 26 under the 50 action of spring 27 to gradually deliver the thread, previously pulled off, to the needle. Obviously the cam member 30 may be so shaped that the retractive motion of the arm 25 and its thread puller may be sudden 55 if such action is desired.

In the modification shown in Fig. 3 the rod 34 is preferably manually operated so that the operation of the arm 25 and its thread puller in the thread pulling direction is approximately simultaneous with the 60 operation of straining the thread by the lifting of the work holder and in some cases this construction is preferred as the operation of the thread pulling or restraining 65 means and the movement of the work holder

or thread straining means may be so timed that they act, in effect, to strain the thread in opposite directions to break said thread.

Having thus described my invention I claim as new and desire to secure by Letters Patent—

1. A sewing machine comprising a head, stitch forming means, operating means therefor, a rotary member having a cam, a pair of thread engaging members mounted 75 on the head, a spring actuated member operating relatively to said thread engaging members, means connected with said spring actuated member and in operative relation to said cam to effect the operation of this 80 member against its spring, a button clamp, and means to operate the button clamp to strain the thread.

2. A sewing machine comprising a head, stitch forming means, operating means 85 therefor, a thread tension, and a pair of complementary thread breaking devices one of which acts to draw and hold a supply of thread prior to the thread breaking operation, and means to operate said devices. 90

3. A sewing machine comprising a head, stitch forming means, operating means therefor, a thread tension, and a pair of complementary thread breaking devices both located above the work, means to operate 95 one of said devices to draw off a supply of thread and to hold said supply of thread during the operation of the other said device and to give up said supply of thread at or about the re-starting of the machine. 100

4. A sewing machine comprising a head, stitch forming means, operating means therefor, a thread tension, and a pair of complementary thread breaking devices, means for operating one of said devices during the operation of the machine to draw thread out of its normal feeding path and adapted to permit said latter device to react to permit the thread to move back into 110 said path.

5. A sewing machine comprising a head, stitch forming means, operating means therefor, a thread tension, and a pair of complementary thread breaking devices one of which is a work holder, a work holder 111 actuating cam, and means to operate the other of said devices from said cam.

6. A sewing machine comprising a head, stitch forming means, operating means therefor, a thread tension, and a pair of complementary thread breaking devices one of which is a work holder, means to effect 12 a predetermined series of actuations of said work holder, and mechanism actuated through said means to bring the other of said devices in position to resist the movement of the thread at a predetermined point attained by said work holder in said actuations.

7. A sewing machine comprising a head, 13

stitch forming means, operating means therefor, a thread tension, and a pair of complementary thread breaking devices one of said devices being a work holder and the other being mounted to swing to carry the thread out of its normal feeding path, and mechanism for effecting a predetermined series of actuations of said work holder, and a progressive positioning movement of the other said device.
